UNITED STATES PATENT OFFICE.

HOMER L. BOYLE, OF LANSING, MICHIGAN.

AEROPLANE.

1,418,522.

Specification of Letters Patent. Patented June 6, 1922.

Application filed September 11, 1918. Serial No. 253,574.

To all whom it may concern:

Be it known that I, HOMER L. BOYLE, a citizen of the United States, residing at Lansing, county of Ingham, State of Michigan, have invented certain new and useful improvements in Aeroplanes, of which the following is a specification.

This invention relates to improvements in aeroplanes.

10 The main object of this invention is to provide in an aeroplane an improved automatic balancing means.

15 Further objects, and objects relating to structural details, will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

30 Fig. I is a side elevation of a structure embodying the features of my invention, the parts being shown mainly in conventional form, a portion of the rudder being broken away.

35 Fig. I^a is a detail view partially in vertical section showing the arrangement of one of the body balancing wheels and its operation connections.

40 Fig. II is a detail view on a line corresponding to line 2—2 of Fig. I, showing the arrangement of the balancing wheels on the planes.

45 Fig. III is a detail section on a line corresponding to line 3—3 of Fig. II.

40 Fig. IV is a detail vertical section on a line corresponding to line 4—4 of Fig. V.

Fig. V is a detail section on a line corresponding to line 5—5 of Figs. II and IV.

45 Fig. VI is a detail side elevation showing an adaptation of my improvement to a plane of the rear or push propeller type.

Fig. VII is a detail view on a line corresponding to line 7—7 of Fig. VI.

50 Fig. VIII is a detail section on a line corresponding to line 8—8 of Fig. VII.

Fig. IX is a detail vertical section on a line corresponding to line 9—9 of Fig. X, showing another modification or adaptation of my improvements.

Fig. X is a detail horizontal view on a line corresponding to line 10—10 of Fig. IX.

Fig. XI is a detail view on a line corresponding to line 11—11 of Fig. X.

Fig. XII is a detail vertical longitudinal section on a line corresponding to line 12—12 of Fig. XIII, through a plane embodying still another form of my invention.

Fig. XIII is a horizontal section on a line corresponding to line 13—13 of Fig. XII.

Fig. XIV is a detail section on a line corresponding to line 14—14 of Fig. XIII.

Fig. XV is a detail longitudinal vertical section through a plane showing a still further embodiment or adaptation of my improvements.

Fig. XVI is an enlarged detail section on a line corresponding to line 16—16 of Fig. XVII.

Fig. XVII is an enlarged detail section on a line corresponding to line 17—17 of Fig. XV.

Fig. XVIII is a detail section similar to that of Fig. XVI, showing a modification in the control valve.

Fig. XIX is a detail vertical longitudinal section through the plane showing still another embodiment of my invention having electrical control electrically driven balancing wheels.

Fig. XX is a diagrammatic view showing conventionally the wiring of the structure shown in Fig. XIX.

Fig. XXI is a side view of a flying machine of the rear propeller type, showing another adaptation or embodiment of my improvement.

Fig. XXII is an enlarged detail vertical section on a line corresponding to line 22—22 of Fig. XXI.

In the drawing, similar reference characters refer to similar parts throughout the several views, and the sectional views are taken looking in the direction of the little arrows at the ends of the section lines.

Referring to the drawing, 1 represents the body or fuselage of an aeroplane, 2 and 3 the planes, and 4 the driving propeller thereof. These parts are all shown conventionally.

To automatically maintain the balance of the machine under varying conditions of use, I provide a rear tail balancing wheel 5, a front balancing wheel 6, and a pair of

side or wing balancing wheels 7. The front and rear or tail and head balancing wheels 5 and 6 are disposed centrally of the body and above the same, while the wing or side 5 balancing wheels 7 are disposed under the upper wing and towards the outer ends thereof. These balancing wheels are of the propeller type. 8 illustrates the crank shaft of the motor indicated at 9.

10 I provide a vertical driving shaft 10 and a horizontal driving shaft 11, the horizontal driving shaft being connected to the crank shaft of the motor by suitable mechanism, shown conventionally at 12, and controlled 15 by the lever 13. The connections for the engine to the shaft 10 are not illustrated.

16 The spindles 14 and 15 of the front and rear propellers are disposed at the ends of the shaft 11 at right angles thereto and have 20 sleeves 16 thereon carrying facing connected beveled friction gears 19, either of which is adapted to be brought into mesh with the gears 20 on the shaft 11, the normal position of the gears 19 being neutral 25 as shown in Fig. I^A. Details of the connections for the other body balancing propeller are not shown as they are duplicates of those shown in Fig. I^A.

26 The sleeve 16 is splined to the shaft 15 30 and is held in its neutral position when the machine is balanced by means of the weight 21 carried by the lever 22 pivoted at 23, the lever being provided with an arm 24 engaging the sleeve as shown in Fig. I^A.

35 When the machine becomes out of balance the weight shifts the sleeve 16 bringing one of the gears 19 into mesh with the driving gear 20 according to the direction of the tilting and thus drives the balancing wheel 40 or propeller in the required direction to return the machine to its normal or balanced position.

40 Through the control lever the balancing wheels may be thrown out of operation. 45 The wing balancing wheels or propellers are carried by the vertical spindles 25, the balancing propellers having friction gears 26 thereon. The driven shafts 27 are supported by the bearings 28 and 29 so as to 50 permit axial or longitudinal adjustment of these shafts.

55 The shaft 10 is provided with a beveled gear 30, while the shafts 27 are provided with a coacting gear 31. The shaft 27 has pairs of facing beveled gears 32 splined thereto to coact with the gears 26 of the spindles 25. The gears 32 are automatically adjusted either to a neutral position or to bring either of the gears 32 into engagement 60 with its coacting gear on the spindle 25 by means of the weight 33 pivoted at 34 to engage the collar 35. This collar is connected by the rods 35' to the pairs of gears 32 so that when the machine tilts, the gears 32 65 are shifted to automatically bring one or

the other thereof into engagement with the balancing wheel spindle gears 26, driving the balancing wheels to reestablish the equilibrium of the plane whenever it is destroyed. 70

75 The weights 33 are enclosed in housings 36 on the under side of the wings. With the parts thus arranged the balancing propellers are automatically controlled through the connections described by the weights so that effective balancing of the machine is maintained.

80 The parts of the aeroplane illustrated are shown mainly in conventional form as the details of these parts form no part of my present invention.

85 In the modification shown in Figs. VI-VIII inclusive, the propeller 37 is disposed at the rear of the short body 38. In approximately the horizontal plane of upper plane, I mount front and rear balancing wheels 40 and 41 respectively, and side balancing wheels 42. 43 represents the vertical driving shaft, the driving means therefor not being illustrated.

90 Front and rear driven shafts 44 and 45 respectively, and the driven shafts 46 for the side balancing wheels are mounted on suitable bearings on the under side of the plane 39.

95 The vertical shaft 43 is provided with a gear 47, while the shafts 44, 45 and 46 are provided with gears 48 meshing with the gear 47.

100 The balancing wheels 40, 41 and 42 are provided with friction gears 50 while the shafts 44, 45 and 46 have pairs of facing beveled friction gears 51 splined thereto to coact with the gears 50. Weights 53 are mounted at 54 within casings 54' and connected to the gears 51 by the rods 51' so that as the weights swing the gears 50 and 51 are brought into and out of driving engagement, thus automatically connecting the balancing wheels with their driving means. 110 With this arrangement all of the balancing wheels are driven from a single driving shaft.

115 In the modification shown in Figs. IX, X and XI, I provide a driving shaft 55 disposed longitudinally on the under side of the plane and having a gear 56 meshing with the gear 57 on the power shaft 58.

120 On the ends of the shaft 55, I spline friction driving wheels 59 to coact with the disks 60 carried by the side balancing wheels. To automatically shift these friction driving wheels 59, I provide weights 61 which are pivoted on the main frame and connected by links 62 with the friction driving disks 59. 125 By shifting the gears 59 axially the speeds of the balancing wheels are controlled.

130 In the modification shown in Figs. XII, XIII and XIV, the balancing wheels 63 are provided with driven disks 64. The shaft 65

has splined thereto the friction gears 66. In their normal position as shown in Fig. XIII, the driving disks 66 are positioned centrally of the disks 64 so that practically no speed is imparted thereto. When, however, the shifting or tilting of the aeroplane actuates the weights, the disks 66 are shifted to one side of the center so that the balancing propellers are driven with varying

10 speeds.

In the modification shown in Figs. XV to XVII, inclusive, I provide a pneumatic driving means for the balancing wheels 73. By this pneumatic driving means the air is delivered through pipes 68 from the supply connection 69. This supply connection is controlled by the valve 70 which is normally in the position shown in Fig. XVI with its port communicating with both pipes 68. When, however, the machine tilts the valve is actuated by the weight 71 cutting off one pipe 68 and giving an increased portage to one of the motors 72. A pressure tank 74 is provided in the air supply line.

25 In Fig. XVIII, I show a modification in which the valve 70' is arranged so that normally both conduits 68 are cut off, that is, they are cut off when the machine is in balance.

30 In the modification shown in Figs. XIX and XX, I show balancing wheels 75 provided with electric motors 78. These motors are controlled by the weight 79 adapted to coact with contact pins 80 when the weight 35 swings from its neutral position. The connections are shown diagrammatically in Fig. XX. I do not describe them in detail as they will be understood by those skilled in this art.

40 In the modification shown in Figs. XXI and XXII, the balancing wheels 81 are mounted below the plane 82. Their spindles 83 are provided with bevel gears 84. A pair of gears 85 are mounted on the driven shaft 86 which is provided with a gear 87 meshing with a gear 88 on the driving shaft 89. The gears 85 are rotatably mounted on the shaft 86 and either one or the other connected thereto through the friction disks 90 which are splined to the shafts and adjusted longitudinally thereon by the rod 91. This rod is controlled by the weight 92 pivoted at 93 and connected to the rod at 94. As the weight swings to the tilting of the plane, the rod is moved longitudinally and one or the other of the clutch members 90 brought into engagement with its gear so that the propeller wheels are driven in one direction or the other.

50 With this arrangement of parts, I provide an aeroplane structure which is automatically balanced and supported against longitudinal or side tilting.

I have illustrated and described several 65 modifications and adaptations of my im-

provements. Parts are shown mainly in conventional form for convenience in illustration.

Having thus described my invention, what I claim as new and desire to secure by Letters Patent, is:

1. In a flying machine, the combination with a body, a plane and a driving propeller, of balancing wheels disposed horizontally at the front and rear ends of the body and provided with vertical driven spindles, a driving shaft disposed longitudinally of the body and provided with beveled driving gears, means for controlling said driving shaft, pairs of connected facing beveled driven gears splined to said balancing wheel spindles to coact with said driving gears, and independent pivoted controlling weights for said driven gears adapted to automatically hold them out of driving engagement with said driving gears when the body is in its longitudinally balanced position and to shift one or the other of the pair of driven gears into driving engagement upon the body assuming an unbalanced position.

2. In a flying machine, the combination with a body, a plane and a driving propeller, of balancing wheels disposed horizontally at the front and rear ends of the body and provided with vertical driven spindles, a driving shaft disposed longitudinally of the body and provided with beveled driving gears, pairs of connected facing beveled driven gears splined to said balancing wheel spindles to coact with said driving gears, and independent pivoted controlling weights for said driven gears adapted to automatically hold them out of driving engagement with said driving gears when the body is in its longitudinally balanced position and to shift one or the other of the pair of driven gears into driving engagement upon the body assuming an unbalanced position.

3. In a flying machine, the combination of a balancing wheel provided with a spindle, a driving gear, means for controlling said driving gear, pairs of facing beveled gears splined to said balancing wheel spindle to coact with said driving gear, and a pivoted control weight therefor adapted to automatically hold said gears normally out of driving engagement with said driving gear or to bring one or the other thereof into driving engagement therewith, all co-acting as specified.

4. In a flying machine, the combination of a balancing wheel provided with a spindle, a driving gear, pairs of facing beveled gears splined to said balancing wheel spindle to coact with said driving gear, and a pivoted control weight therefor adapted to automatically hold said gears normally out of driving engagement with said driving

gear or to bring one or the other thereof into driving engagement, all coacting as specified.

5. In a flying machine, the combination with a body, a plane and a driving propeller, of a pair of lateral balancing wheels provided with beveled gears, a shaft, pairs of facing gears splined to said shaft to be shifted so that either is brought into driving engagement with said gears on said balancing wheels or to a neutral position, and automatic means adapted to shift said gears on said shafts.

6. In a flying machine, the combination of a balancing wheel provided with a gear, 15 a shaft, a pair of gears splined to said shaft to coact with said balancing wheel gear and

a controlling weight adapted to shift said gears on said shaft, all coacting as specified.

7. In a flying machine, the combination of a balancing wheel provided with a gear, 20 a shaft, a pair of gears splined to said shaft to coact with said balancing wheel gear and automatic means adapted to shift said gears on said shaft, all coacting as specified.

In witness whereof, I have hereunto set 25 my hand and seal in the presence of two witnesses.

HOMER L. BOYLE. [L.S.]

Witnesses:
